UNITED STATES PATENT OFFICE.

EDWARD H. WELLS, OF MONTCLAIR, NEW JERSEY, ASSIGNOR TO THE BABCOCK & WILCOX COMPANY, OF BAYONNE, NEW JERSEY, A CORPORATION OF NEW JERSEY.

WATER-TUBE BOILER.

1,150,913.

Specification of Letters Patent. Patented Aug. 24, 1915.

Application filed August 6, 1913. Serial No. 783,268.

To all whom it may concern:

Be it known that I, EDWARD H. WELLS, a citizen of the United States, residing at Montclair, in the county of Essex and State 5 of New Jersey, have invented certain new and useful Improvements in Water-Tube Boilers, of which the following is a full, clear, and exact description, reference being had to the accompanying drawings, forming 10 part of this specification, in which—

Figure 1 is a sectional side elevation of one embodiment of my invention, and Fig. 2 a sectional end elevation thereof.

Similar reference numerals indicate similar parts in the several views.

Referring to the drawings the numeral 1 designates the front and rear walls, and 2 the side walls of the setting. A boiler for the utilization of waste heat is shown, the 20 gases entering through the flue 3, but it is applicable to any class of service. The boiler consists of a longitudinal steam and water drum 4 supported by the front and rear walls, or by other convenient means, 25 centrally of the setting, and a parallel mud drum 5 also located centrally of the setting. Expanded into these drums are tubes divided into as many banks as may be desired for a particular installation, three banks, 30 designated 6, 7 and 8, respectively, being shown, each bank consisting of five rows of tubes. The mud drum 5 is supported above the floor of the setting so that the soot and dust which falls from the tubes, or from 35 the hot gases, is deposited in the space at the bottom and at the sides of the drum, from whence it can be readily removed through the doors 16. The front end of drum 5 is protected by the inner wall of flue 3.

The rows of tubes of banks 6, 7 and 8 may be set so that there shall be a space between each two rows, as in a Stirling boiler, to provide for the renewal of the inner tubes 45 without cutting out some of the others. By bending the upper and lower ends of the tubes so that they enter the drums 4 and 5 radially it is possible for the rows of tubes to be extended from one side wall to the 50 other, resulting thereby in a substantial gain in the heating surface.

Between the first and second banks of

tubes is a vertical baffle 9 extending from the foundation upwardly around the mud drum, and supported by two rows of tubes 55 10. Between the second and third banks is a vertical baffle 11 extending from the drum 4 downwardly, and supported by two rows of tubes 12. The baffles 9 and 11 extend from one side wall of the setting to the other, and are at right angles to the drums 60 4 and 5. In order to secure an efficient heat absorption of the gases in passing over the tubes, the gases are deflected into the banks of tubes and across the tubes by horizontal 65 baffles 13, supported upon suitable jackets, and extending between the banks of tubes and the tubes 11 and 12 which support the vertical baffles. Inclined shelves 14 may be introduced at the front and rear banks, as 70 shown.

The boiler may be used with or without a superheater. One position that the superheater may occupy is at the rear of the first bank of tubes. The superheater shown consists of a series of U-shaped tubes 15 lying in substantially vertical planes and with their lower ends connected to cross boxes or headers 17' and 17 located immediately 75 above the mud drum. A pipe 18 leads from the steam space of drum 4 to box 17'. A suitable steam outlet leads from box 17. In this position, the hot gases after passing across the lower portion of the tubes of the first bank will strike the superheater, after 80 which the gases will be deflected, by the baffle 13 immediately above the loops 15, forward into the upper portion of the first bank of tubes. With the superheater in the position shown the maximum obtainable 85 superheat may be secured with a given amount of superheating surface, and the superheater tubes at the same time will be protected from over-heating, as the hot 90 gases will first pass through the first bank of boiler tubes before striking the superheater. Further, the superheater is in a position where the lower part of the boxes are 95 readily accessible, and the arrangement is such that the ends of the superheater tubes 100 where they enter the boxes may be readily inspected. The construction of the boiler does not limit the position of the superheater to that shown in the drawings, for

example, the superheater may be placed in the second pass of the boiler, either in front or at the rear of the second bank of tubes, and may be so located if only a limited amount of superheat is desired.

Other advantages incident to the construction and arrangement of the parts above described are, that every part of the boiler heating surface can be readily inspected; all parts of the tube surface can be readily dusted by means of an air or steam lance; all soot and dust can be readily removed from the space below and at the sides of the mud drum; the vertical baffles 9 and 11 are held securely in position by the boiler tubes on each side of the same; and a considerable gain in the heating surface is secured by having a single steam and water drum and a single mud drum placed centrally of the setting so that the rows of tubes may extend from one side wall to the other.

In the operation of the boiler shown in the drawings, the gases enter the boiler at the front and first flow over the lower part of the first bank of tubes and the superheater loops, then over the upper part of the first bank of tubes, across and downwardly over the second bank of tubes, then across and upwardly over the rear bank of tubes to the stack outlet 15.

With the three banks of tubes shown in the drawings the flue gases leave the boiler near the upper part of the setting when they enter at the bottom of the first bank of tubes, and leave the boiler near the lower part of the setting when they enter at the top of the first bank of tubes.

The spacing apart of the banks of tubes, as shown in the drawings, enables a man to enter between the banks for purposes of cleaning the tube surfaces, or removing or replacing tubes.

What I claim and desire to secure by Letters Patent of the United States is:—

1. A boiler having a single longitudinal steam and water drum and a single longitudinal mud drum, water tubes arranged in separated banks in planes at right angles to the longitudinal axes of the drums and connecting said drums, said banks being separated sufficiently to allow entrance between them, vertical baffles between the banks and water tubes separated from the banks and supporting said baffles, said supporting tubes being expanded into the drums.

2. A boiler having a single longitudinal steam and water drum and a single longitudinal mud drum, water tubes arranged in separated banks in planes at right angles to the longitudinal axes of the drums and connecting said drums, said banks being separated sufficiently to allow entrance between them, vertical baffles between the banks, the

first of said baffles at the rear of the first bank extending upward around the mud drum, and water tubes separated from the banks and supporting said baffles, said supporting tubes being expanded into the drums.

3. A boiler having a single longitudinal steam and water drum and a single longitudinal mud drum, water tubes arranged in separated banks in planes at right angles to the longitudinal axes of the drums and connecting said drums, said banks being separated sufficiently to allow entrance between them, vertical baffles between the banks and water tubes separated from the banks and supporting said baffles, said supporting tubes being expanded into the drums, and shelves projecting from the vertical baffles toward the separated banks of water tubes.

4. A boiler having a single longitudinal steam and water drum and a single longitudinal mud drum, water tubes arranged in separated banks in planes at right angles to the longitudinal axes of the drums and connecting said drums, said banks being separated sufficiently to allow entrance between them, an inlet for the gases near the lower part of the first bank, vertical baffles between the banks at right angles to the longitudinal axes of the drums to give the gases up and down passes to the outlet flue, and water tubes separated from the banks and supporting said baffles.

5. A boiler having a single longitudinal steam and water drum and a single longitudinal mud drum, water tubes arranged in separated banks in planes at right angles to the longitudinal axes of the drums and connecting said drums, said banks being separated sufficiently to allow entrance between them, vertical baffles between and parallel with the banks, water tubes supporting said baffles, and a superheater in the pass between the first bank and the first of said baffles.

6. A boiler having a single longitudinal steam and water drum and a single longitudinal mud drum, water tubes arranged in separated banks in planes at right angles to the longitudinal axes of the drums and connecting said drums, said banks being separated sufficiently to allow entrance between them, vertical baffles between and parallel with the banks, water tubes separated from the banks and supporting said baffles, and a superheater in the pass between the first bank and the first of said baffles.

7. A boiler having a single longitudinal steam and water drum and a single longitudinal mud drum, water tubes arranged in separated banks in planes at right angles to the longitudinal axes of the drums and connecting said drums, said banks being separated sufficiently to allow entrance between

them, vertical baffles between and parallel with the banks, water tubes separated from the banks and supporting said baffles, and a superheater in the pass between the first bank and the first of said baffles, said superheater forming the major portion of the heating surface in said pass.

In testimony whereof I have hereunto signed my name in the presence of two subscribing witnesses.
